UNITED STATES PATENT OFFICE.

ALOIS A. RITTER, OF RACINE, WISCONSIN, ASSIGNOR TO HARTMANN TRUNK COMPANY, OF RACINE, WISCONSIN, A CORPORATION OF WISCONSIN.

DESIGN FOR A TRUNK DOWEL.

Application filed July 2, 1925. Serial No. 13,974. Term of patent 7 years.

To all whom it may concern:

Be it known that I, Alois A. RITTER, a citizen of the United States, residing at Racine, in the county of Racine and State of Wisconsin, have invented a new and original and ornamental Design for Trunk Dowel, of which the following is a description, reference being had to the accompanying drawing, forming part thereof.

In the drawing, Fig. 1 is a side view of the new design of trunk dowel; and Fig. 2 is an edge view thereof.

I claim:

The ornamental design for a trunk dowel, as shown.

ALOIS A. RITTER.
